UNITED STATES PATENT OFFICE.

JESSE BRIGGS, OF STUYVESANT, NEW YORK.

IMPROVEMENT IN CLAMPS FOR HOLDING SAWS.

Specification forming part of Letters Patent No. **56,519**, dated July 24, 1866.

To all whom it may concern:

Be it known that I, JESSE BRIGGS, of Stuyvesant, in the county of Columbia and State of New York, have invented a new and Improved Clamp for Holding Saws while being Filed; and I do hereby declare that the following is a full, clear, and exact description thereof, which will enable those skilled in the art to make and use the same, reference being had to the accompanying drawings, forming part of this specification, in which—

Figure 1 is a side view of my invention, partly in section, as indicated by the line *x x*, Fig. 2; Fig. 2, a plan or top view of the same.

Similar letters of reference indicate like parts.

This invention relates to a new and improved clamp for holding saws while being sharpened or filed.

The object of the invention is to obtain a simple and cheap implement for the purpose specified, and one which may be very readily manipulated.

The implement or device is composed of two parts, A A', which may be termed "frames," and they are of right-angular form, the lower parts, *a*, being of V-shape, and the upper parts being each composed of two uprights, *b b*, connected at their upper ends by bars B B', which serve as jaws to clamp the saw-blade.

The part A, at its bend or angle at each side, is provided with a lateral projecting pin, *c*, and the other part, A', is provided at each side, at corresponding points, with a hook-projection, *c'*, and these projections are fitted over

the pins *c*, on which they work as fulera. (See Fig. 1.)

On the rear of the part or frame A' of the device there is fitted a cam, C, provided with a handle or lever, D, said cam bearing or working against the rear of the frame A.

The jaws B B' are opened and closed by operating the cam C. When the handle or lever D is shoved or drawn toward the jaws B B', as indicated in red, Fig. 1, the jaws B B' will be closed so as to clamp firmly the saw-blade, and when said handle or lever is moved in the opposite direction the jaws will be opened, as shown in black.

The two parts or frames A A' may each be cast in one piece and adjusted together without any trouble or work whatever.

The cam and handle may be of wrought or malleable cast-iron.

The expense of manufacture, it will be seen, will be extremely small.

The frame A may be cast with a cross-bar, *a'*, having a hole in it for a screw to pass through in order to secure the device to any fixture.

I claim as new and desire to secure by Letters Patent—

The construction and arrangement of the frames A A', jaws B B', hook-projections *c'*, pins *c*, cam C, and lever D, in the manner herein described and represented.

JESSE BRIGGS.
